UNITED STATES PATENT OFFICE.

JOHN JOSEPH HOURIGAN, DECEASED, BY ALEXANDER G. WATT, ADMINISTRATOR, OF RANDWICK, NEAR SYDNEY, NEW SOUTH WALES, AUSTRALIA.

CUTTER-LID CLOSURE FOR CIRCULAR CANS HAVING HERMETICALLY-SEALED TAGGERS-TIN TOPS.

1,149,055.

Specification of Letters Patent.

Patented Aug. 3, 1915.

Application filed May 27, 1914. Serial No. 841,336.

To all whom it may concern:

Be it known that I, ALEXANDER GEORGE WATT, a subject of the King of Great Britain and Ireland, residing at Avoca street, 5 Randwick, near Sydney, in the State of New South Wales, Commonwealth of Australia, and administrator of the estate of JOHN JOSEPH HOURIGAN, deceased, the inventor of certain new and useful Improvements in 10 Cutter-Lid Closures for Circular Cans Having Hermetically-Sealed Taggers-Tin Tops, do hereby declare the following to be a specification of the said invention.

This invention relates to improvements in 15 cutter lid closures for circular cans having hermetically sealed taggers tin tops and it is directed to the provision of a slip-on rotatable lid having an integrally formed cutting nib or ripper of effective and improved 20 construction.

Hitherto there have been attached independently formed cutting nibs or rippers to the lids of cans secured in such a way that they slide radially in slots or guides formed 25 near the edges of the lids. The sliding movement is necessary to permit the depending cutting nib being moved outwardly so as to normally lie between the depending portion of the lid and the top of the can. To 30 open the can in such construction, the lid is removed and the cutting nib or ripper then forced inwardly to such a position that it will pierce the top of the can when the lid is forced thereon, when the said top may be 35 removed by giving the lid a complete rotation. The disadvantages incident to the above-mentioned construction are the comparatively great cost of manufacture and the necessity of having the lids made much 40 larger than the cans to accommodate the cutting nib when resting in its normal or inoperative position.

In order that the invention may be readily understood reference will now be made to 45 the accompanying sheet of explanatory drawings wherein:

Figure 1 is a view in plan of part of a slip-on lid having an integrally formed cutting nib constructed according to the present invention. Fig. 2 is a view in sectional side elevation of Fig. 1 taken on the dotted line 1—1. Figs. 3 and 4 are views in transverse section of part of the lid, showing the

cutting nib in its inoperative and operative positions, respectively. Fig. 5 is an inverted 55 plan view of Fig. 4. Figs. 6 and 7 are views in plan of part of a lid showing modifications in the shape of the cutting nib.

In these drawings wherein like characters of reference indicate the same or corresponding parts in the different views, *a* designates the lid, in the top and near the edge of which is forced a V-shaped slit *b* having the apex pointing to the center thereof. The dies or swages employed to form the slit *b* 60 also press up the metal around the same as shown at *c* and give to the pointed nib *d* thus formed a concaved formation transversely to insure it having a required degree of stiffness or cutting strength to resist all 65 bending or twisting strains when in operation. The dies that emboss the nib *d* to give it its concave formation also form a step *e* at its base which is adapted to abut against a bulb or "heel" *f* formed on the inside of 70 the lid *a* and between the base of the nib and the adjacent edge of the said lid.

A lid *a* provided with an integrally formed cutting nib or ripper *d* as above described can fit snugly on a tin and no provision is 75 required for the disposal of the said nib.

The cutting nib may be given the shape shown in Figs. 6 and 7 of the drawings or it can be given any other formation preferred or found most suitable for a particular re- 85 quirement.

To open the top *g* of a can—see dotted lines in Figs. 3 and 4—the cutting nib *d* is brought into action by bending it downwardly as by a finger nail or a penknife 90 until it assumes a perpendicular position and is parallel with the rim of the lid. When the cutting nib is moved to this position and as shown in Fig. 4 of the drawings, the stepped portion *e* at its base bears upon 95 the bulb or "heel" *f* which prevents it going beyond the perpendicular and insures its perfect rigidity when in action. After depressing the cutting nib *d* the same can be forced through the tagger tin top *g* and 100 the lid *a* rotated to remove the same in the ordinary way.

The concave formation of the cutting nib *d* besides preventing it becoming distorted in action also causes the ragged edge of the 105 tagger tin to be turned over neatly after the

cutting edge has been passed, thereby leaving a smooth edge for the hand to remove the contents of the can.

After use the cutting nib *d* can be pressed back into place thus nearly closing the orifice in the lid and allowing the can to be used for any length of time without fear of the lid becoming sufficiently loose to fall off in handling. Moreover, a cutting nib so formed has considerable rigidity notwithstanding that it is constructed of relatively thin sheet metal, and the outer curved face in operation has a rubbing bearing against the inner face of the rim and insures an even and clean cut being made, through the tagger top as near as possible to the edge thereof.

What I do claim is:—

1. A can lid comprising in combination, an integrally formed piercing and cutting nib integral with the can lid and adapted to be bent downwardly out of its normal plane into operative position, said cutting nib being provided with a stepped portion and an inwardly projecting bulb, the said stepped portion being adapted to bear against said inwardly projecting bulb when the nib is bent downwardly in operative position.
2. A can lid having a rim and an integrally formed piercing and cutting nib of V-shaped formation with the apex pointing toward the center of the lid and formed with a stepped portion at its base, and an inwardly projecting bulb the stepped part

of the nib being adapted to bear thereupon when the same is pressed downwardly to lie parallel with the rim of the lid, substantially as described.

3. A lid for cans having an integrally formed cutting nib, a stepped portion at the base of said nib, and an inwardly projecting bulb located between the base of the nib and the adjacent side portion of the lid, and an embossment on that part of the lid from which the cutting nib is constructed and surrounding said cutting nib in its inoperative position, substantially as described.

4. A can lid having a rim and comprising in combination a piercing and cutting nib integral with the can lid, said nib being curved transversely and formed with a step at its base, an inwardly projecting bulb located between the base of the nib and the adjacent side of the lid, the stepped portion of the nib being adapted to lie adjacent to and parallel with the bulb when the nib is pressed downwardly, in an operative position.

In witness whereof I have signed this specification in the presence of two witnesses.

A. G. WATT,

Administrator of the estate of John Joseph Hourigan.
